UNITED STATES PATENT OFFICE

122,839

DESIGN FOR A DRESS

Etta Marcus Horblit, Roxbury, Mass.

Application August 24, 1940, Serial No. 94,613

Term of patent 3½ years

To all whom it may concern:

Be it known that I, Etta Marcus Horblit, a citizen of the United States and a resident of the city of Roxbury, in the county of Suffolk and State of Massachusetts, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress as shown in Fig. 1.

I claim:

The ornamental design for a dress, substantially as shown.

ETTA MARCUS HORBLIT.
